United States Patent

Des. 236,159

Patented July 29, 1975

236,159

COPY MACHINE

Roger L. Larson, Roseville, Minn., and Samuel M. Highberger, Bloomfield Township, Mich., assignors to Minnesota Mining and Manufacturing Company

Filed Dec. 21, 1973, Ser. No. 427,044

Term of patent 14 years

Int. Cl. D16—03

U.S. Cl. D61—1 Q

FIG. 1

FIG. 2

FIG. 3

FIG. 4

FIG. 5

FIG. 6

FIG. 7

FIG. 1 is a front perspective view of a copy machine showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view thereof.

We claim:

The ornamental design for a copy machine, substantially as shown and described.
